HOLSTER FOR HAMMERS AND THE LIKE

William A. Feuerer, 1802 Oak St., Apt. 5,
Santa Monica, Calif. 90405

Filed Oct. 21, 1966, Ser. No. 4,363

Term of patent 14 years

(Cl. D2—400)

FIG. 1 is a perspective view of a holster for hammers and the like, showing my new design;

FIG. 2 is a side elevational view of the side not shown in FIG. 1.

FIG. 3 is a rear elevational view; and

FIG. 4 is a top plan view.

I claim:

The ornamental design for a holster for hammers and the like, substantially as shown and described.
